UNITED STATES PATENT OFFICE.

AXEL HOLMSTRÖM, OF STOCKHOLM, SWEDEN.

ETCHING MACHINE.

Application filed June 19, 1922. Serial No. 569,425.

To all whom it may concern:

Be it known that I, AXEL HOLMSTRÖM, a subject of the King of Sweden, residing at Drottningholmsvagen 9, Stockholm, Sweden, 5 have invented a certain new and useful Improvement in Etching Machines, of which the following is a specification.

My invention relates to etching machines and more particularly to etching machines 10 in which the acid is sprayed upon the plates to be etched by means of a revolving paddle.

The main object of my invention is to provide inexpensive means whereby the paddle may be easily and quickly put in and 15 taken out.

A further purpose is to provide a box with an opening at one end of the shaft sufficiently large for easy removal through it of the shaft and paddle, in conjunction with 20 a readily removable door, preferably of stoneware or other acid resistant material, normally fitting about the shaft and closing the opening.

A further purpose is to provide the door 25 with a portion substantially fitting an outer surface of the box about the opening and adapted to press upon a gasket upon this outer surface.

A further purpose is to provide the door 30 with an inwardly extended portion above the shaft to shield the shaft from falling liquor.

A further purpose is to provide a common support for the bearing of the shaft and for 35 clamping means for holding the door in place.

Further purposes will appear in the specification and in the claims.

I have preferred to illustrate my invention 40 by a few forms only of the many in which it may appear, selecting these because they are practical, efficient and inexpensive and which at the same time well illustrate the principles of my invention.

45 Figure 1 is a sectional diagrammatical view to illustrate the position and duty of a paddle used in etching.

Figure 2 is a side elevation of an etching box equipped with my invention.

50 Figure 3 is a broken section through line 3-3 of Figure 2.

Figure 4 is an enlarged broken detail section of Figure 3.

Figure 5 is a front elevation of another 55 form.

Figure 6 is a section through line 6-6 of Figure 5.

Figure 7 is a broken front elevation of another form.

Figure 8 is a section through line 8-8 60 of Figure 7.

In all drawings like numbers refer to like parts.

Referring to the drawings and describing 65 in illustration and not in limitation:

In etching devices of this character the acid is conveniently placed within a stoneware box and is thrown upon the plates by means of a stoneware paddle mounted upon a shaft that is protected from the acid by 70 being covered with rubber or other protective coating. The bearings of the shaft are placed outside of the box to be away from the acid, the shaft extending clear through the box and having a bearing at each end. 75

It occasionally happens that a paddle is broken, as by reason of an operator accidentally dropping a plate upon it, and when this happens the paddle and shaft must be removed, the broken part replaced and the 80 whole then put back into the box.

The level of the etching liquor within the stoneware box is well below the shaft. A revolving blade upon the paddle dips into the liquor, picks it up and casts it against 85 a baffle in such a way as to spray it upon plates placed along the opposite wall of the box.

The etching process is well illustrated 90 diagrammatically in Figure 1 where the stoneware tank 14 is filled with etching liquor to a level $a-a$ considerably below the shaft 15 which carries the stoneware paddle 16. The shaft 15 extends through the sides of the box to suitable bearings 17, 95 as seen in Figure 3. The revolving paddle casts the etching liquor into the baffle space 18 and past the baffle 19 against plates 20 set upon a groove 21 along the stoneware rest plate 22. The box has a removable 100 cover 23 and a glass cover portion 24 usually left in place. A fan 25 draws a continuous stream of air into the box through an opening 26 and carries off the fumes with the air to a suitable chimney not shown.

105 The operation of the mechanism to etch

a plate involves removing the cover, if it be on, placing the plate 20 upon the groove 21, replacing the cover 23, starting the paddle and continuing its operation for a suitable time drenching the plate with the etching liquor, stopping the paddle, removing the cover and withdrawing and washing the plate.

The paddle 16 may be made in a number of sections so that if there should be breakage, as by reason of an operator dropping a plate upon the paddle, a short section only of the paddle would have to be replaced.

The shaft at each end turns within a universal joint bearing 17. The shaft turns directly in a box 27 which is pivoted horizontally at 28 and vertically at 29, the box 27 being free to turn vertically on the pivot 28 and the pivot 28 being free to turn horizontally on the pivot 29.

At one side of the box I provide an opening 30 sufficiently large to permit easy removal through it of the paddle and shaft and I close this opening by means of a stone-ware door 31 apertured for the shaft and approximately filling and fitting the hole 30 with a flange portion 32 for fitting against the outer wall of the box around the opening.

This door 31 is provided with an inwardly projecting boss 33 for protecting the shaft from the acid and is somewhat recessed at 34 to make it less heavy.

To carry the bearing 17 I provide wooden bars 35 and 36, one on each side of the box, held together by tie rods 37. These wooden bars 35 and 36 carry the universal joint bearings 17, and the bar 35 also carries brackets 38 and set screws 39 for holding the door 31 in place.

I preferably provide a gasket between the face of the flange 32 and the face of the box, against which gasket the door is pressed. Rubber or like material may be used. Vaseline or asphaltum will also serve the purpose.

The shaft carries a driving pulley 40 which is driven by any suitable motor, not shown, and which in turn drives the pulley 41 of the fan 25.

Should it at any time become necessary to take out the shaft and paddle, all that is necessary is to remove the pulley 40, the brackets 38 and the bearings 17, after which the door 31 may be lifted out and the whole shaft with its paddles may be slid out longitudinally through the opening 30.

In the door shown in Figures 2 and 4 the hole is circular and the gate is likewise circular and surrounds the shaft.

Figures 5 and 6 show another form in which the gate is generally rectangular and does not wholly surround the shaft but fits down over the shaft, having for this purpose a suitable slot. The lower edge of the

opening has then a semi-circular groove 42 which half way surrounds the shaft and the rectangular gate has a similar semi-circular groove 43 through the full thickness of the gate and a slot 44 through the flange portion. The door is held in place in the same way as shown in Figures 2 and 3, Figures 8 and 9 show another form.

In Figure 8 the arrangement is somewhat similar to that of Figure 5 but the gate does not project into the opening 30'. The upper edge of the lower side of the hole has a semicircular groove 42' as with the form of Figure 5.

The outside of the box has a guiding portion 45 to position the door and this may interlock with the door to form runways 46 as shown in Figure 8. These runways are preferably made to project from the side of the box so that the gate may slide out-side of the box.

It is evident that these various forms are all broadly the same invention, and I am well aware that in view of my invention and disclosure other forms and variations will become evident to those skilled in the art, to meet individual whim or particular need, and I claim all such modifications and variations in so far as they fall within the reasonable spirit and scope of my invention.

Having thus described my invention, what I claim as new and desire to secure by Letters Patent is:—

1. In an etching machine, a box internally resistant to etching liquor and having an opening, a shaft normally passing through the opening, a paddle resistant to etching liquor mounted upon the shaft within the box and adapted to pass through the opening and a closure about the shaft to close the opening.

2. In an etching machine, a shaft, a paddle resistant to etching liquor mounted upon the shaft, a box within which the paddle is adapted to operate and having an opening in its side surrounding the shaft in use and adapted to pass the paddle and shaft from the box, and a door internally resistant to etching liquor and with the shaft approximately closing the opening.

3. In an etching machine, a shaft, a paddle resistant to etching liquor mounted upon the shaft, a pottery box within which the paddle is adapted to operate and having an opening in its side normally surrounding the shaft and adapted to pass the paddle and shaft from the box, and a door of pottery with the shaft approximately closing the opening.

4. In an etching machine, a shaft, a paddle resistant to etching liquor mounted upon the shaft, an acid-resistant box, within which the paddle is adapted to operate and having an opening in its side normally surrounding the shaft and adapted to pass the

5 paddle and shaft from the box, a door internally resistant to etching liquor with the shaft approximately closing the opening, and a member projecting inwardly from the 10 door to cover an adjacent portion of the shaft.

10 5. In an etching machine, a box internally resistant to etching liquor, a shaft, a paddle 15 resistant to etching liquor mounted upon the shaft and adapted to operate within the box, an opening in the side of the box surrounding the shaft and adapted to pass the paddle and shaft from the box, a door internally 20 resistant to etching liquor, with the shaft 25 approximately closing the opening, having an inwardly projecting portion approximately fitting the contour of the opening and an external flange to mate with the external rim of the box about the opening 30 and means for pressing the door toward the box flange.

35 6. In an etching machine, a shaft, a paddle 40 resistant to etching liquor mounted upon the shaft, an acid-resistant box within which the paddle is adapted to operate and having an opening in its side normally surrounding 45 the shaft and adapted to pass the paddle and shaft from the box, a door internally 50 resistant to etching liquor, with the shaft approximately closing the opening, a clamp external of the box for normally holding the door in place, a bearing for the shaft, and common means for supporting the 55 clamp and the bearing.

approximately closing the opening and 30 clamping means for holding the door in place.

7. In an etching machine, a shaft, a paddle 35 resistant to etching liquor mounted upon the shaft, an acid-resistant box within which the paddle is adapted to operate and having an opening in its side normally surrounding the shaft and adapted to pass the paddle and shaft from the box, a door internally 40 resistant to etching liquor, with the shaft 45 approximately closing the opening, and a screw clamp external of the box for normally holding the door in place.

8. In an etching machine, a shaft, a paddle 50 resistant to etching liquor mounted upon the shaft, an acid-resistant box within which the paddle is adapted to operate and having an opening in its side normally surrounding the shaft and adapted to pass the paddle and shaft from the box, a door internally 55 resistant to etching liquor, with the shaft approximately closing the opening, a clamp external of the box for normally holding the door in place, a bearing for the shaft, and common means for supporting the clamp and the bearing.

AXEL HOLMSTRÖM.
